United States Patent Office

Des. 181,897
Patented Jan. 14, 1958

181,897

RADIO CABINET

Robert E. Bowers, El Cerrito, Calif., assignor to R-E-B, Inc., El Cerrito, Calif., a corporation of California

Application April 12, 1957, Serial No. 45,727

Term of patent 14 years

(Cl. D56—4)

Fig. 1

Fig. 2

Fig. 1 is a front perspective view of a radio cabinet, showing my new design; and

Fig. 2 is a rear perspective view thereof.

The side not shown is the same in appearance as the side shown.

I claim:

The ornamental design for a radio cabinet, as shown and described.
